His Attorney.

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

ELECTRIC HEATING UNIT.

1,367,341.

Specification of Letters Patent.

Patented Feb. 1, 1921.

Application filed November 15, 1918. Serial No. 262,722.

To all whom it may concern:

Be it known that I, CHARLES C. ABBOTT, a citizen of the United States, residing at Pittsfield, county of Berkshire, State of 5 Massachusetts, have invented certain new and useful Improvements in Electric Heating Units, of which the following is a specification.

My invention relates to electric heating elements of the type in which a resistance conductor is inclosed in a metallic sheath and insulated from it by a thin dense layer of insulating material. Resistance elements of this general type are now in common use 10 in electric heaters and the like and are known as "sheath wire" elements. One of the characteristic features of this resistance element is that the insulating layer between the conductor and the sheath is very thin and very closely compacted so that the conductor is in very intimate thermal relation 15 with the sheath. The usual method of producing such a resistance element is to locate a straight resistance conductor, which may 20 be called the core wire, centrally of a metallic tube which is to form the sheath and fill the tube with an insulating powder, such as magnesia, so as to completely embed and properly center the core wire. The ends 25 of the tube are then plugged, suitable provision being made for the ends of the core wire which extend beyond the tube, and the tube is subjected to a reducing process. 30 The result of this operation is the reduction 35 of both the sheath and the core wire, with the consequent compacting of the insulating material. The arrangement is such that when the core wire is reduced to its desired size, the insulating material is so thoroughly 40 compacted that it becomes practically a unit with the core wire and may be drawn or rolled like a solid metal. This element, being supplied with the proper terminals, constitutes an efficient heating unit since it is 45 exceedingly rugged and requires no insulating support, the core wire being well insulated and protected from mechanical injury. Such a resistance element naturally has its 50 limitations, since the space available for the heating element is not always sufficient to contain the length of conductor necessary to produce the required resistance. This is particularly true where the element is to be used on a circuit of 220 v. or higher.

55 I have found that sheath wire having a

helical or sinuous conductor instead of a straight core wire may be produced having all the advantages of the above described straight conductor sheath wire in addition to advantages of its own. The principal advantage of this form of unit lies in the fact that a much greater length of core wire may be contained in a given space so that the unit is much more compact and self contained and is readily adapted to the higher voltages without occupying increased space. There are other advantages, however, both from the standpoint of the manufacture and of the utility of the unit itself which are important. One of these advantages arises from the fact that the core wire is not reduced in diameter by the reduction of the sheath. Since the core wire is not drawn down, a grade of wire which is difficult to draw, but which may be more suitable, may be used. A greater thickness of insulating material which will give greater margin of safety to the electrical insulation may also be used since the core wire is not reduced, whereas in reducing straight core wire, if the thickness of the insulating material is above a certain maximum, the core wire will not be drawn down properly. Furthermore the core wire retains its surface left by the drawing dies, and a smaller wire may be used than would be safe where it is drawn down in the tube. There are also certain other advantages, such as simplified terminal connections, greater latitude in the grade and character of the metals used for the sheath.

In accordance with my invention, therefore, a sinuous or helical resistance element is centrally located in a metallic sheath filled with powdered insulating material which is compacted to a high degree so as to form a very dense insulating body having relatively high heat conducting properties, so that the heat will be transmitted to the sheath at the greatest possible rate consistent with good electrical insulation, thereby producing a mechanically rugged resistance element capable of embodying a high resistance in a relatively small space.

My invention will best be understood by reference to the accompanying drawings in which Figure 1 is a sectional view of the resistance conductor mounted in a tube ready for filling; Fig. 2 is an end view of the same; Fig. 3 is a view of the filled tube.

partially broken away to show the terminals; Fig. 4 is a view showing the unit reduced; and Fig. 5 is a detail of the terminal.

In the manufacture of sheath wire in accordance with my invention I form a sinuous resistance element 10 which is preferably in the form of a helix, the material being a high resistance material such as nickel-chromium alloy. This conductor is supported centrally of the tube 11 which may be of any desired metal capable of being drawn or swaged down. The helix when wound may be a closed helix but, when it is supported in the tube, it is stretched so as to separate the turns and at the same time the tension will tend to keep the helix in a central position. In order to form enlarged terminals upon the helix and at the same time furnish a suitable support for the helix for the filling and subsequent drawing operation, I mount each end of the helix on a rod 12, as shown in detail in Fig. 5. This rod, which is preferably of the same material as the core wire, so as to prevent any galvanic action between the core and the terminals, is provided with an enlarged pointed head 13 upon which the helix fits. The end of the wire is then wound on to the inclined surface of the head and on to the rod for a short distance, the end being finally inserted in a slot 14 in the rod. The edges of the slot are then swaged over the end of the wire so as to make a good electrical contact and securely fix the end of the wire to the terminal. The two ends of the helix are thus provided with terminal supports which are passed through holes in the caps 15 and 16 which are fitted over the ends of the tube, the terminals being secured to the caps by set screws 17 and 18. The wire is preferably under tension, as above pointed out, and is supported so that the helix will be kept in its proper central position. The cap 15 is provided with a funnel 19 having perforations 20 through which the insulating material is poured into the tube. The insulating material employed is one which has the quality of compacting into a solid mass and at the same time has high electrical insulating properties and high heat conductivity. Magnesium oxide is a suitable material for this purpose. When the tube is filled and the material somewhat compacted by some means, as for instance, by jarring or vibrating the sheath tube, the caps 15 and 16 are removed and the ends of the tube permanently closed. As shown, this is accomplished by means of metallic disks 21 and 22 over which the metal is bent, the ends of the terminals passing through the disk and being formed into heads 23 and 24. The tube is now in the condition shown in Fig. 3.

The tube is now subjected to a reducing process which consists in passing it through a swaging or rolling machine. The amount

of reduction necessary is not great since its purpose is largely to compact the powdered material around the helix. Ordinarily a reduction in diameter and consequent lengthening of the tube, such as is represented by 70 the relative dimensions of the parts shown in Figs. 2 and 3, will accomplish this purpose. I have found, for instance, that a tube having an outside diameter of $\frac{3}{8}$ " and an internal diameter of $\frac{1}{8}$ " when properly reduced will have an outside diameter of 75 and an elongation of about 15%.

One of the results obtained by such a reducing process is that the electrical resistance of the resistance conductor decreases 80 to a certain extent and this was found to be due to the fact that the diameter of the wire increases. Upon investigation it was found that there is a direct relation between the decreased resistance and the increase in 85 the length of the tube, that is, the ratio between the resistance of the helix before swaging and after swaging is equal to the ratio between the length of the tube after 90 swaging and before swaging. The reason 95 for this seems to be that since the number of turns of the helix remains the same, while the diameter of the helix is decreased, the length of each turn is also decreased. The helix is not materially extended by drawing 100 it out so as to separate the turns but by compressing the helix without substantial movement of the helix with reference to the surrounding insulation. The insulating material is thus very thoroughly compacted all 105 around the helix. It is, therefore, possible to determine very accurately just what the resistance of the helix will be upon a given reduction, or to put it in another way, it is possible to determine just when a certain 110 resistance is reached by measuring the length of the tube. When the tube is properly reduced, the sheath and insulating material are cut away so as to expose the terminal for some length, as shown in Fig. 4, 115 and the unit is then ready for use.

While I have described my invention as embodied in concrete form in accordance with the provisions of the patent statutes, it should be understood that I do not limit my 115 invention thereto, since various modifications thereof will suggest themselves to those skilled in the art without departing from the spirit of my invention, the scope of which is set forth in the annexed claims. 120

What I claim as new and desire to secure by Letters Patent of the United States, is,—

1. An electric heating unit comprising a metallic sheath, powdered heat refractory 125 insulating material compacted to a hard dense mass within said sheath and a sinous resistance element embedded in said mass so as to readily conduct heat from the resistance element to the sheath. 130

2. An electric heating unit comprising a metallic sheath, powdered heat refractory insulating material compacted to a hard dense mass within said sheath and a helix 5 resistance element embedded in said mass so as to readily conduct heat from the resistance element to the sheath. 60
3. An electric heating unit comprising a metallic sheath, powdered heat refractory 10 insulating material compacted to a hard dense mass within said sheath, a sinuous resistance element embedded in said mass so as to readily conduct heat from the resistance element to the sheath and terminal 15 members secured to the element and projecting from the sheath. 65
4. An electric heating unit comprising a metallic sheath, powdered heat refractory insulating material compacted to a hard 20 dense mass within said sheath, a sinuous resistance element embedded in said mass so as to readily conduct heat from the resistance element to the sheath and terminal members supporting the ends of the element 25 and projecting from the sheath. 70
5. An electric heating unit comprising a metallic sheath, powdered heat refractory insulating material compacted to a hard dense mass within said sheath, a sinuous resistance element embedded in said mass so 30 as to readily conduct heat from the resistance element to the sheath and terminal members inserted in and secured to the element and having reduced end portions projecting from the sheath. 75
6. An electric heating unit comprising a metallic sheath, powdered heat refractory insulating material compacted to a hard dense mass within said sheath, a helical resistance element embedded in said mass so 40 as to readily conduct heat from the resistance element to the sheath and terminal members secured to the ends of the element and projecting from the sheath, said members having enlarged ends upon which the element is 45 mounted. 80
7. The method of forming a resistance unit which consists in mounting a sinuous resistance element in a metallic sheath, filling the space around the element with a heat refractory insulating material and reducing the sheath sufficiently to thoroughly compact the insulating material around the resistance element. 85
8. The method of forming a resistance unit which consists in mounting a helical resistance element in a metallic sheath, filling the space around the element with a heat refractory insulating material and reducing 90
- the sheath to compact the insulating material and compress the element without substantially separating its turns. 95
9. The method of forming a resistance unit which consists in securing enlarged terminals to a helical resistance element, 100 mounting said element and terminals in a metallic sheath with ends projecting therefrom and the element under tension, filling the space around the element with a heat refractory insulating material and reducing the sheath sufficiently to thoroughly compact the insulating material around the element and the terminals. 105
10. The method of forming an electric heating unit which consists of mounting a helical resistance element in a metallic sheath, filling the space around the element with a heat refractory insulating material and then compacting the material around the element. 110
11. The method of forming an electric heating unit which consists of mounting a helical resistance element in a metallic sheath, filling the space around the element with a heat refractory insulating material, compacting the material around the element and finally compacting the material still further by reducing the sheath. 115
12. The method of forming an electric heating unit which consists of mounting a helical resistance element in a metallic sheath, filling the space around the element with a heat refractory insulating material, compacting the material around the element by a vibrating or jarring action upon the material and finally compacting the material still further by reducing the sheath. 120
13. The method of forming an electric heating unit which consists in fitting terminal members into the end of a helical resistance conductor and mounting the same in a metallic sheath, filling the space around the element with a heat refractory insulating material and then compacting the material around the element and terminal to fix them against displacement. 125
14. An electric heating unit comprising a metallic sheath, powdered heat refractory insulating material compacted to a hard dense mass within said sheath, a helical resistance element embedded in said mass so as to readily conduct heat from the resistance element to the sheath and terminal members inserted in the element and projecting from the sheath. 130

In witness whereof, I have hereunto set my hand this 13th day of Nov. 1918.

CHARLES C. ABBOTT.

It is hereby certified that in Letters Patent No. 1,367,341, granted February 1, 1921, upon the application of Charles C. Abbott, of Pittsfield, Massachusetts, for an improvement in "Electric Heating Units," an error appears in the printed specification requiring correction as follows: Page 2, line 76, after the word "of" insert $\frac{u}{u}$; and that the said Letters Patent should be read with this correction therein that the same may conform to the record of the case in the Patent Office.

Signed and sealed this 15th day of March, A. D., 1921.

[SEAL.]

M. H. COULSTON,

Commissioner of Patents.

Cl. 219—67.
